File. 1209

Elmer J. Ney, of Lowell, Mass.
Assignor to.

Lowell Manufacturing Company, same place.
Letters Patent No. 1209. Dated Feb. 28. 1860.

The schedule referred to in these Letters Patent and making part of the same.

To all whom it may concern:

Be it known that J. Elmer J. Ney, of Lowell, in the County of Middlesex and State of Massachusetts, have originated and designed a new pattern for Carpets or other fabrics, of which the following is a full, clear and exact description, reference being had to the accompanying drawings, making part of this Specification.

The Corners A, and B, are quarters of a figure in the centers of which are sprigs and leaves. said figures rest upon the plain grounds 1 & 2.

Center C, consists of a group of three large leaves extending towards the center from corners D. and E. are branches supporting flowers 3. and leaves 4. surrounding the grounds 1 and 2, are small groups of leaves and flowers 5. the coral work 6. occupies the remaining portions of the design and surrounds the groups.

The colors employed in the different portions of the design, may be varied to suit the taste and... wish of the manufacturer.

Claim.

What I claim as my invention, and desire to secure by Letters Patent, is the design or pattern for Carpets herein set forth.

Witness,

Oras. F. Salmon, 3
